Development Company, Pittsburgh, Pa., a cor-
poration of Delaware

Application September 27, 1946, Serial No. 699,671

13 Claims. (Cl. 196—28)

1

This invention relates to the desulfurization of light petroleum hydrocarbons and more particularly to a method of contacting light petroleum hydrocarbons with a contact agent to remove sulfur therefrom.

Gasoline and other light cuts obtained from high sulfur crudes such as those from the Permian Basin of West Texas have long been a problem of utmost importance to the refiner. Besides the difficulties involved in handling, these hydrocarbons have undesirable properties such that they are only useful after removal of most of the sulfur.

The difficulties are particularly pronounced with sour cracked gasolines which are more difficult to desulfurize than straight run gasolines. The most practiced commercial process is known as acid treating and it has the distinct disadvantage of not only lowering the quality of the product as judged by octane number but it also involves considerable loss of product.

Mercaptans in gasoline may be converted into disulfides by the process known as "doctor sweetening" and other similar processes. However, the disulfides are not removed but largely remain dissolved in the gasoline resulting in only slight sulfur reduction and generally in a lowering of octane number.

Newer solvent methods such as the "solutizer" and similar processes actually remove mercaptans from gasoline which results in an increase in lead susceptibility, as well as the desired sweetening. These processes do not remove other type sulfur compounds which are allowed to remain in the product.

An object of the present invention is to remove sulfur from light petroleum hydrocarbons with no substantial reduction in olefin content.

A further object of the present invention is to remove sulfur in any form including hydrogen sulfide from light petroleum hydrocarbons with no substantial reduction in olefin content.

These and other objects are achieved by the process of the present invention in which a light petroleum hydrocarbon such as straight run or cracked gasoline or naphtha is passed, together with hydrogen, over a contact agent comprising nickel oxide supported on activated alumina. Temperatures in the range 600° to 800° F. are used.

The process generally comprises mixing the charge with hydrogen and passing the mixture over a contact agent consisting initially of nickel oxide supported on activated alumina. During the reaction the nickel oxide is converted into nickel sulfide and the reaction is discontinued

2

when so much nickel sulfide is present that the end product contains substantial hydrogen sulfide.

Hydrogen is present in the range of from 100 to 1000 cubic feet per barrel of liquid charge. Pressures used are in the range of from 100 to 500 pounds per square inch gauge; a space velocity of from 1.0 and 6.0 volumes of liquid charge per hour per volume of contact agent. It will be understood that the preferred operating conditions for the process necessarily vary depending upon the sulfur content and olefin content of the charge stock but the above conditions generally apply to light petroleum charge stocks. It is undesirable to have hydrogen sulfide in the end product and for this reason when about 50 to 60 per cent of the original nickel oxide becomes nickel sulfide, the contact agent should be regenerated. The regeneration is accomplished by burning the contact agent in the presence of an oxygen containing gas to reconvert it to nickel oxide and to burn off the carbonaceous deposit.

Our process begins with nickel oxide and during the course of reaction this is converted to nickel sulfide thereby removing the sulfur compounds from the charge stock and liberating the oxygen of the nickel oxide as water. There may also be simultaneous reduction of some of the nickel oxide to lower nickel oxides, such as Ni_2O or metallic nickel with concurrent formation of water. Subsequently, part of these lower oxides and/or metallic nickel probably reacts with the sulfur compounds in the charge stock. It is possible that during the reaction the nickel oxide, nickel sulfide, or nickel metal may act as catalysts, but the net result is that of the reaction between nickel oxide and the sulfur. Apparently the use of nickel oxide as the starting material inhibits the cracking activity of the subsequently produced metallic nickel to such an extent that cracking to gas and coke is not excessive. Furthermore, since the total time spent by any of the contact in the metallic state is limited, rapid loss of activity through sintering is avoided as well as decrease in unsaturation. The maximum processing period is limited to the interval during which no substantial amount of hydrogen sulfide is liberated from the reactor.

The presence of hydrogen sulfide in the effluent product indicates that essentially all of the readily available nickel oxide and nickel has been converted to nickel sulfide. At this time it is necessary to regenerate the contact with an oxygen-containing gas which converts the nickel sulfide back to nickel oxide, and simultaneously

removes the sulfur as sulfur dioxide in recoverable concentrations. In general 50-60 per cent of the total nickel oxide may be reacted before regeneration is necessary. This percentage is not invariant but depends on the operating conditions, sulfur content of the charge stock and contact. It has also been found that a minor amount of sulfur remains in the contact mass after regeneration as nickel sulfate. However, this nickel sulfate does not accumulate during subsequent cycles under our preferred conditions and apparently is not disadvantageous. The herein proposed theory of the action of the contact agent should not be interpreted to limit the claims in any manner.

A flow sheet of the equipment for carrying out our desulfurization process is shown in the attached drawing in which the charge stock enters line 1 and is pumped by means of pump 2 through line 3, product heat exchanger 4 and line 5 into heater 6 where it is heated to reaction temperature either before or after mixing with the hydrogen or hydrogen-rich gas from line 29. The mixture of charge and hydrogen or hydrogen-rich gas at the desired reaction temperature passes through line 7, valve 8 and line 9 into the reaction chamber 10 containing the preferred contact. The desulfurized product leaves the reaction chamber by means of line 11, valve 12, line 13, heat exchanger 4 and line 14 into the high pressure separator 15. The liquid product from the high pressure separator passes through line 16, cooler 17, line 18 and valve 19 into a low pressure separator 20. The desulfurized liquid product from the low pressure separator is withdrawn by means of valve 21 and line 22.

Gases from the low pressure separator are released through valve 23 and line 24. The separated gases contain hydrogen which may be recovered for recycle if desired in any conventional manner such as an oil absorption and stripping system. The hydrogen-rich gas from the high pressure separator may also require some hydrogen enrichment which can also be carried out in a conventional manner. These gases normally pass through line 25, are compressed by pump 26, pass through line 27 and admix with fresh or make-up hydrogen from line 28 and valve 36. This hydrogen-rich gas is preheated in heater 6 either separately or in admixture with the charge stock. This mixture then passes through line 7 as described previously.

During this on-stream period valves 30, 31 and 32 remained closed. At the completion of the on-stream period which varies depending on the charge stock and the conditions of reaction, pumps 2 and 26 are turned off and valves 8, 12 and 36 are closed. The pressure is released on contact

bed 10 by means of valve 31 and the reactor is vacuum purged in conventional manner. Alternatively valve 31 and valve 32 may both be opened and the contact purged with an inert gas or steam. The purpose of the purge is to recover valuable hydrocarbons which remain in the contact bed. Following the purge, valve 31 is closed and valves 30 and 32 are opened and an oxygen containing gas is admitted to the reactor by means of line 34, valve 30 and line 9. The admission of this oxygen containing gas in controlled amounts regenerates the contact converting it to nickel oxide and simultaneously forms sulfur dioxide which is vented from the reaction chamber by means of line 11, valve 32 and line 35 together with combustion gases from the carbonaceous deposit. This regeneration off-gas contains recoverable quantities of sulfur dioxide in amounts depending upon the quantity of sulfur originally present as nickel sulfide as well as the oxygen content of the regeneration gas. This sulfur dioxide may be recovered in any normal manner such as by solvent absorption and stripping. The sulfur dioxide-free regeneration off-gas may then serve to dilute the fresh regeneration gas admitted to the reaction chamber. Alternatively the sulfur dioxide-containing regeneration gas may serve to dilute the fresh regeneration gas. After regeneration is complete, inert gas or steam may again be used to flush the system by closing valve 30 and opening valve 31 or the reaction chamber may be vacuum purged. The unit is then put on-stream again by closing valves 31 and 32, opening valves 8, 12 and 36 and starting pumps 2 and 26.

The foregoing description of the apparatus employed has been used as an example only. Multiple or single beds of fixed contact or fluidized contact as well as systems in which the contact is continuously charged and removed from the reaction zone followed by external regeneration are not excluded.

The preferred contact agent was prepared as follows: Dried granular 3 to 6 mesh activated alumina was impregnated with an aqueous nickel nitrate solution followed by drying at 260° F. and subsequent calcining at 800° F. to decompose the absorbed nickel nitrate to nickel oxide. This sequence of impregnation, drying and calcining was twice repeated so that the final product contained 29.3 per cent nickel oxide and 70.7 per cent alumina.

The charge was a West Texas cracked gasoline distillate having a gravity of 54.9° API, a bromine number of 46.4, a specific gravity at 60°/60° F. of 0.7591 and a sulfur weight per cent of 0.24. Following are the results obtained using the conditions indicated:

Cycle No.	Pressure, p. s. i. g.	Space Vel. Vol./Vol. X Hr.	Through-put, Vol./Vol.	Aver. React. T° F.	Hydrogen		Liquid Recovery		Product

This invention is concerned with low boiling petroleum hydrocarbons which for purposes of this application may be defined as those normally liquid petroleum fractions having an ASTM end point up to 600° F. This includes straight run or cracked gasoline and naphtha. The process, however, is particularly suitable to treating cracked sulfur containing gasoline.

While the method of preparation of the contact agent has been described as impregnation, other methods of preparation may be used such as precipitation, decomposition of other nickel salts, etc. However it is essential that low temperatures be used since high calcining temperatures deactivate the alumina.

As described above the preferred operating conditions for the process necessarily vary within certain ranges depending upon the charge stock. In general the conditions are as follows:

Temperature, °F	600-800
Pressure, p. s. i. g	100-500
Space velocity, vol.chg./hr.vol. contact	1.0-6.0
Hydrogen concentration, cu. ft./bbl.	100-1000

At temperatures below 600° F. the desulfurizing activity of the contact diminishes whereas above 800° F. excessive cracking reactions result in decreased product recovery and rapid coke formation which deactivates the contact. At pressures below 100 p. s. i. g. the partial pressure of hydrogen is not sufficient to maintain desulfurizing activity nor to suppress cracking reactions which result in coke formation. Increasing the pressure above 500 p. s. i. g. results in only a slight incremental gain in desulfurization and a decrease in bromine number and is thus not commercially desirable.

Space velocities below 1.0 vol. of charge per hour per volume of contact agent result in excessive cracking and olefin saturation reactions caused by the long contact time and at space velocities above 6.0 the contact time is too short to provide sufficient desulfurization. Hydrogen concentrations below 100 cu. ft. bbl. of charge stock are not sufficient to maintain desulfurization activity nor to suppress cracking reactions properly. Hydrogen concentrations above 1000 cu. ft. per bbl. result in only a slight incremental gain in desulfurization and cause a disadvantageous decrease in bromine number. Higher space velocities and hydrogen concentrations than 6.0 vol. charge per hour per volume contact and 1000 cu. ft. per barrel, respectively, result in insufficient contact time to allow complete reaction of the hydrogen sulfide and it is evolved from the reactor within a relatively short processing period. The volumes of charge stock passed over one volume of contact during the processing period depends on the per cent sulfur in the charge stock and the per cent nickel oxide in the contact but normally is in the range of 10 to 100. This throughput volume is limited by the period during which no hydrogen sulfide is evolved from the contact bed.

The optimum regeneration conditions are approximately:

Temperature, °F	1000-1300
Pressure, p. s. i. g	0-500
Diluent gas to air ratio, vol./vol	0-20

The regeneration temperature is limited to that which does not produce a loss of mechanical strength or activity of the contact agent but at the same time must be sufficiently high to convert nickel sulfide to nickel oxide and burn off

any accumulated coke deposit. The regeneration pressure is adjusted within the indicated range to obtain the optimum regeneration time which will depend on charge stock and operating conditions. The diluent gas to air ratio is adjusted to maintain the desired regeneration temperature and obtain the optimum regeneration time. Diluent gases may include steam, flue gas, regeneration off-gas, etc.

10 The present process has many advantages. Sulfur content of the gasoline is reduced and the bromine number remains essentially unchanged. Clear and leaded octane numbers by both motor and research methods are increased

15 and lead susceptibility is improved. According to the present process doctor sweet gasoline is produced in one step instead of the three steps of acid treating, re-running, and sweetening. In addition, sludge, polymerization and some handling losses are eliminated. As compared to solvent processes the present invention has the advantage that the sulfur content of the product is lower and octane numbers are higher. Further, the present process is more flexible as to the charge since naphthas of higher boiling range may be desulfurized. Charge stocks of low mercaptan content which are essentially unchanged by the solvent processes are desulfurized by our process.

20 These advantages accrue by the use of our process because the sulfur content is reduced and the degree of unsaturation of the product remains essentially the same as the charge. This latter point in particular serves to distinguish our process from other processes employing hydrogen. 25 It is attributable to the use of our specific contact agent and operating conditions which yield very specific desulfurizing action and very little hydrogenation of olefins.

20 The process is not to be confused with hydrogenation processes using metallic nickel as a catalyst. We have found that if a nickel oxide is reduced with hydrogen prior to charging the light petroleum oil, the efficiency of desulfurization is markedly reduced due to the high cracking activity of reduced nickel which results in excessive gas yields and rapid formation of a coke deposit on the contact.

30 In the following claims when we speak of absorbing sulfur from the hydrocarbon vapors it is to be understood to mean that the sulfur contained in the vapors, in whatever form that it is present therein, is taken up by the reactant due to the formation of nickel sulfide.

35 What we claim is:

35 1. A process for desulfurizing low boiling petroleum hydrocarbons without substantial change in olefin content comprising passing the vapors thereof over a contact agent consisting initially of unreduced nickel oxide supported on activated alumina at a temperature in the range of from 600° to 800° F. and at a pressure in the range 100 to 500 pounds per square inch gauge, and in the presence of hydrogen, absorbing sulfur from the vapors to form nickel sulfide, terminating the 40 passage of vapors before a substantial amount of hydrogen sulfide appears in the effluent and before about 60 per cent of the available nickel content of the contact has been converted into nickel sulfide, regenerating the contact by converting 45 the nickel sulfide thus formed into nickel oxide and re-using the regenerated contact in the process.

40 2. A process for desulfurizing low boiling petroleum hydrocarbons without substantial change in olefin content comprising passing the vapors

thereof over a contact agent consisting initially of unreduced nickel oxide supported on activated alumina at a temperature in the range of from 600° to 800° F. at a pressure above about 100 pounds per square inch gauge at a space velocity in the range 1.0 to 6.0 liquid volumes of charge per hour per volume of contact agent, and in the presence of hydrogen, absorbing sulfur from the vapors to form nickel sulfide, terminating the passage of vapors before a substantial amount of hydrogen sulfide appears in the effluent and before about 60 per cent of the available nickel content of the contact has been converted into nickel sulfide, regenerating the contact by converting the nickel sulfide thus formed into nickel oxide and re-using the regenerated contact in the process.

3. A process for desulfurizing low boiling petroleum hydrocarbons without substantial change in olefin content comprising passing the vapors thereof over a contact agent consisting initially of unreduced nickel oxide supported on activated alumina at a temperature in the range of from 600° to 800° F. at a pressure above about 100 pounds per square inch gauge and in the presence of hydrogen, said hydrogen being present in a concentration range of from 100 to 1000 cubic feet per barrel of charge, absorbing sulfur from the vapors to form nickel sulfide, terminating the passage of vapors before a substantial amount of hydrogen sulfide appears in the effluent and before about 60 per cent of the available nickel content of the contact has been converted into nickel sulfide, regenerating the contact by converting the nickel sulfide thus formed into nickel oxide and re-using the regenerated contact in the process.

4. A process for desulfurizing low boiling petroleum hydrocarbons without substantial change in olefin content comprising passing the vapors thereof over a contact agent consisting initially of unreduced nickel oxide supported on activated alumina at a temperature in the range of from 600° to 800° F. and at a pressure in the range 100 to 500 pounds per square inch, at a space velocity in the range 1.0 to 6.0 liquid volumes of charge per hour per volume of contact agent and in the presence of hydrogen, said hydrogen being present in a concentration range of from 100 to 1000 cubic feet per barrel of charge, absorbing sulfur from the vapors to form nickel sulfide, terminating the passage of vapors before a substantial amount of hydrogen sulfide appears in the effluent and before about 60 per cent of the available nickel content of the contact has been converted into nickel sulfide, regenerating the contact by converting the nickel sulfide thus formed into nickel oxide and re-using the regenerated contact in the process.

5. A process for desulfurizing straight run gasoline comprising passing the vapors thereof over a contact agent consisting initially of unreduced nickel oxide supported on activated alumina at a temperature in the range of from 600° to 800° F. and at a pressure in the range 100 to 500 pounds per square inch gauge, at a space velocity in the range 1.0 to 6.0 liquid volumes of charge per hour per volume of contact agent and in the presence of hydrogen, said hydrogen being present in a concentration range of from 100 to 1000 cubic feet per barrel of charge, absorbing sulfur from the vapors to form nickel sulfide, terminating the passage of vapors before a substantial amount of hydrogen sulfide appears in the effluent and before about 60 per cent of the available nickel content

of the contact has been converted into nickel sulfide, regenerating the contact by converting the nickel sulfide thus formed into nickel oxide and re-using the regenerated contact in the process.

6. A process for desulfurizing cracked gasoline without substantial change in olefin content comprising passing the vapors thereof over a contact agent consisting initially of unreduced nickel oxide supported on activated alumina at a temperature in the range of from 600° to 800° F. and at a pressure in the range 100 to 500 pounds per square inch gauge, at a space velocity in the range 1.0 to 6.0 liquid volumes of charge per hour per volume of contact agent and in the presence of hydrogen, said hydrogen being present in a concentration range of from 100 to 1000 cubic feet per barrel of charge, absorbing sulfur from the vapors to form nickel sulfide, terminating the passage of vapors before a substantial amount of hydrogen sulfide appears in the effluent and before about 60 per cent of the available nickel content of the contact has been converted into nickel sulfide, regenerating the contact by converting the nickel sulfide thus formed into nickel oxide and re-using the regenerated contact in the process.

7. A process for desulfurizing petroleum naphtha without substantial change in olefin content comprising passing the vapors thereof over a contact agent consisting initially of unreduced nickel oxide supported on activated alumina at a temperature in the range of from 600° to 800° F. and at a pressure in the range 100 to 500 pounds per square inch gauge, at a space velocity in the range 1.0 to 6.0 liquid volumes of charge per hour per volume of contact agent and in the presence of hydrogen, said hydrogen being present in a concentration range of from 100 to 1000 cubic feet per barrel of charge, absorbing sulfur from the vapors to form nickel sulfide, terminating the passage of vapors before a substantial amount of hydrogen sulfide appears in the effluent and before about 60 per cent of the available nickel content of the contact has been converted into nickel sulfide, regenerating the contact by converting the nickel sulfide thus formed into nickel oxide and re-using the regenerated contact in the process.

8. A process for desulfurizing low boiling petroleum hydrocarbons without substantial change in olefin content comprising passing the vapors thereof over a contact agent consisting initially of unreduced nickel oxide supported on activated alumina at a temperature in the range of 600° to 800° F. at a pressure above about 100 pounds per square inch gauge and in the presence of hydrogen, absorbing sulfur from the vapors to form nickel sulfide, terminating the passage of vapors before a substantial amount of hydrogen sulfide appears in the effluent and before about 60 per cent of the nickel content of the contact has been converted into nickel sulfide, regenerating the contact by converting the nickel sulfide thus formed into nickel oxide and re-using the regenerated contact in the process.

9. A process for desulfurizing low boiling petroleum hydrocarbons without substantial change in olefin content comprising passing the vapors thereof over a contact agent consisting initially of unreduced nickel oxide reactant supported on activated alumina at a temperature in the range of 600° to 800° F. at a pressure above about 100 pounds per square inch gauge and in the presence of hydrogen, absorbing sulfur from the vapors

to form nickel sulfide, terminating the passage of vapors when the reactant contains about 50 per cent of nickel sulfide, regenerating the contact by converting the nickel sulfide thus formed into nickel oxide and re-using the regenerated contact in the process.

10. A process for desulfurizing low boiling petroleum hydrocarbons without substantial change in olefin content comprising passing the vapors thereof over a contact agent consisting initially of un-reduced nickel oxide reactant supported on activated alumina at a temperature in the range of 600° to 800° F. at a pressure above about 100 pounds per square inch gauge and in the presence of hydrogen, absorbing sulfur from the vapors to form nickel sulfide discontinuing the passage of said vapors when the reactant contains about 50 per cent of nickel sulfide, regenerating the contact agent by passing an oxygen containing gas over it and re-using the regenerated contact in the process.

11. A process for desulfurizing low boiling petroleum hydrocarbons without substantial change in olefin content comprising passing the vapors thereof over a contact agent consisting initially of un-reduced nickel oxide reactant supported on activated alumina at a temperature in the range of 600° to 800° F. at a pressure above about 100 pounds per square inch gauge and in the presence of hydrogen, absorbing sulfur from the vapors to form nickel sulfide discontinuing the passage of said vapors when the reactant contains about 50 per cent of nickel sulfide, regenerating the contact agent by passing an oxygen-containing inert gas over it at a temperature in the range 1000° to 1300° F. and pressure of from atmospheric to 500 pounds per square inch and re-using the regenerated contact in the process.

12. A process for desulfurizing low boiling petroleum hydrocarbons without substantial change in olefin content comprising passing the vapors thereof over a contact agent consisting initially of un-reduced nickel oxide reactant and activated alumina at a temperature in the range 600° to 800° F. at a pressure above about 100 pounds per square inch gauge and in the presence of hydrogen, absorbing sulfur from the vapors to form nickel sulfide discontinuing the passage of said

vapors when the reactant contains about 50 per cent of nickel sulfide, regenerating the contact agent by passing a diluent gas-air mixture there-over at a temperature in the range 1000 to 1300° F. and a diluent gas to air ratio of 0 to 20 and re-using the regenerated contact in the process.

13. A process for desulfurizing cracked gasoline without substantial change in olefin content comprising passing the vapors thereof over a contact agent consisting initially of un-reduced nickel oxide supported on activated alumina at a temperature of about 700° F., a pressure of about 250 p. s. i. g., a space velocity of about 4 volumes of charge per hour per volume of contact agent in the presence of hydrogen, said hydrogen being present in the concentration of about 500 cubic feet per barrel of charge, absorbing sulfur from the vapors to form nickel sulfide, terminating the passage of vapors before a substantial amount of hydrogen sulfide appears in the effluent and before about 60 per cent of the available nickel content of the contact has been converted into nickel sulfide, regenerating the contact by converting the nickel sulfide thus formed into nickel oxide and re-using the regenerated contact in the process.
